CENTRALIZED TRAFFIC CONTROLLING
SYSTEM FOR RAILROADSWilliam D. Hailes, Brighton, N. Y., assignor to
General Railway Signal Company, Rochester,
N. Y.

Application May 7, 1937, Serial No. 141,322

11 Claims. (Cl. 177—353)

This invention relates to centralized traffic controlling systems for governing traffic on railroads and it more particularly pertains to the communication part of such systems.

In a centralized traffic controlling system of the type contemplated by this invention, the switch and signals are distributed at field stations throughout the territory and are governed from the control office by means of the transmission of controls over a two-wire line circuit interconnecting the control office with the several field stations. Indications relating to the condition of the switches and signals, as well as track occupancy and unoccupancy, are transmitted over the same two-wire line circuit to the control office.

The two line wires connecting the control office with all of the field stations comprise a single circuit, which serves the purpose of carrying the impulses used to select the required station and for transmitting controls to the selected station. This single circuit also serves to carry the indication impulses from a transmitting station to the control office for registering a calling station in the office and for transmitting indications from the registered station to the indication signal devices in the office.

The present system is of the station selection coded duplex type, that is, it is operated through cycles of operation for the transmission of controls and/or the transmission of indications during each cycle. When controls are transmitted, a station selecting code is first applied to the line circuit for selecting the desired station and then the controls are transmitted thereto by means of additional coded impulses. When indications are transmitted, the particular field station which is transmitting first transmits a station registering code for registering or identifying this particular station in the control office and then the indications from the registered or identified station are transmitted to the control office by means of additional coded impulses.

For the transmission of controls, a predetermined number of impulses of selected polarities are placed on the line circuit for operating the apparatus in the control office and at the field stations in synchronism through cycles of operations, irrespective of the polarity of the impulses. The distinctive polarity of the impulses of each series makes up a code combination which determines the particular station to be selected and the controls to be transmitted thereto.

For the transmission of indications, the transmitting station inserts an impulser in the line

circuit during a portion of each time space between the impulses which are applied to the line circuit from the control office. During a cycle for the transmission of indications, the impulser at the transmitting field station provides the indication code by inserting positive, negative or zero impulses in between the stepping impulses applied to the line circuit in the control office during such a cycle.

One important feature of the present invention resides in the manner in which indication impulses are sandwiched in between the control impulses, with these indication impulses being of distinctive polarity or being absent entirely. By such an arrangement, the line circuit may be coded at each step of the system in any one of three ways for transmitting one of a choice of three indications per step.

Another feature of the present invention resides in the manner in which the apparatus functions for the transmission of controls by means of polar impulses applied to the line circuit, in the same cycle during which this line circuit is used for the transmission of indications by means of polar impulses.

Still another feature of the present invention resides in the manner in which the indication impulser is inserted in the line at the transmitting field station, during the time spaces between impulses applied to the line in the control office, and the manner in which the line circuit is pieced through at other field stations not transmitting during this particular cycle of operations.

A further feature of the present invention resides in the manner in which the line circuit in the control office is switched from one line relay, which operates during the transmission of impulses from energy supplied in the control office, to another line relay which functions to receive and register the polarity of the indication impulses, which are applied to the line between the first mentioned impulses.

These characteristic features of the present invention, thus briefly stated, and other features of the present embodiment will be explained more in detail in the following description of one arrangement for carrying out the features of the invention, while various other characteristic features, functions and advantages of a system embodying this invention will be in part pointed out and in part apparent as the description progresses.

In describing the invention in detail, reference will be made to the accompanying drawings, in which those parts having similar features and

functions are designated throughout the drawings by like letter reference characters, which are generally made distinctive either by reason of distinctive exponents representative of their location in the system, or by means of preceding numerals representative of their order of operation during a cycle and in which:—

5 Figs. 1A and 1B (with Fig. 1B placed below Fig. 1A) illustrate the apparatus and circuit arrangement employed at the control office for providing means whereby the operator may select the stations and govern the switches and signals at the selected stations; and also for providing means whereby indications may be received from 10 the various field stations throughout the territory.

15 Figs. 2A and 2B (with Fig. 2B placed below Fig. 2A) illustrate the apparatus and circuit arrangement employed at a typical field station for receiving the polar control impulses which are 20 applied to the line circuit, for causing the station stepping mechanism to operate in synchronism with the office stepping mechanism and for providing the control code combinations. Figs. 2A and 2B also illustrate the apparatus and circuit 25 arrangement employed at the field station for providing for the transmission of indications to the control office.

30 For the purpose of simplifying the drawings and facilitating in the explanation, various parts and circuits have been shown diagrammatically and certain conventional illustrations have been employed. The drawings have been made more for the purpose of making it easy to understand the operation of the system, rather than with 35 the idea of illustrating the specific arrangement that would preferably be employed in practice. For example, the various relays and their contacts are illustrated in a conventional manner and symbols are used to indicate the connections 40 to the terminals of batteries or other source of current instead of showing all of the wiring connections to these terminals. Certain relays are shown on certain drawings in dotted blocks connected to the full line blocks, to indicate that the 45 relays illustrated by the dotted line blocks are the same relays illustrated by the full line blocks appearing on some other drawing.

50 The symbols (+) and (−) are employed to indicate the positive and negative terminals respectively of suitable batteries or other sources of current and the circuits with which these symbols are used always having current flowing in the same direction, that is, from (+) to (−). The detailed circuits for operating the stepping 55 relays in the control office and at the illustrated field station have been omitted for the sake of simplicity, with dotted line connection 20 in Fig. 1A and dotted line connection 120 in Fig. 2A indicating that the stepping relay banks are controlled by contacts on the FP and SB relays. In 60 the following description it will merely be mentioned that the stepping relays pick up and release during certain impulse and time space periods, and for an understanding of the detailed circuits 65 for effecting this operation of the stepping relay banks, reference may be had to Powell Patent, No. 2,058,824, issued October 27, 1936, which patent shows the control of similar stepping relays by contacts on the FP and SAP relays, the latter 70 corresponding to relay SB of the present disclosure.

Furthermore, the method of station selection by means of the polar impulses applied to the control line from the control office is not illustrated in detail, since this is accomplished by

means of the SO relays at the stations (such as relay SO¹ of Fig. 2A), in the same manner as disclosed in Fig. 3 of the T. J. Judge et al. application, Ser. No. 640,062, filed October 28, 1932, now Patent No. 2,082,544, granted June 1, 1937. 5

10 The detailed circuit arrangement and operation of the present system may be more readily understood by considering the drawings, with Fig. 2A placed to the right of Fig. 1A and with Figs. 1B and 2B placed in positions above mentioned, with correspondingly numbered lines in alignment.

15 *Control office equipment.*—The control office includes a control machine having a group of control levers for each field station, a miniature track layout corresponding to the actual track layout in the field and various indicating lamps, or the like, together with the apparatus and circuits to accomplish the desired functions of the 20 system.

25 For example, the apparatus for one track switch is illustrated as comprising switch machine lever SML (see Fig. 1A), starting or station button STB and code jumpers 13 and 14, together with the apparatus and circuits to accomplish the 30 desired functions of the system. Since it is well known how the miniature track layout is arranged and how the various control levers are associated with the control office equipment, the major portion of this apparatus has been omitted, it only being deemed necessary to illustrate two code jumpers and a switch machine lever, since other control levers effect the transmission of controls in a manner similar to that which 35 will be described for lever SML.

40 The system is started into a cycle of operations from the control office by the momentary actuation of button STB, which effects the picking up of relays C and CD as indicated by means of dotted line 11. The detailed circuits for accomplishing this function may be as disclosed in detail in the above mentioned Judge et al. application and consequently it is not believed necessary to more than mention that relays C and CD are picked up at the beginning of a cycle, in response to the operation of button STB, when controls 45 are to be transmitted during such cycle.

45 A neutral line relay F and a polar line relay R are provided in the control office and alternately inserted in the line circuit for purposes which 50 will be explained in detail. Resistance DR is a compensating resistance for maintaining the resistance in the line substantially constant irrespective of whether relay F is picked up or not. Repeating relay FP repeats the impulses applied 55 to the line circuit from the control office, this relay following the operations of line relay F during each cycle of operations. Slow acting relays SA and SB are provided for defining the bounds 60 of an operating cycle, that is, these relays are picked up in sequence at the beginning of a cycle, are held up by the impulses during this cycle and are then dropped out during the clearing out period at the end of the cycle.

65 Associated with the line and line repeating relays is a bank of stepping relays, comprising half-step relay VP and stepping relays 1V, 2V and 3V. Impulse controlling relay E serves to control the beginning and the end of each impulse period, this relay being operated in response to the step-by-step operations of the stepping relay bank and in turn controlling the energization and deenergization of the line circuit by picking up and dropping the selected code sending relay PC or NC, these latter relays serving to apply positive 70 75

or negative impulses respectively to the line circuit.

Relay OC is picked up at the beginning of each cycle of operations and is maintained energized throughout the cycle, as long as relay E continues to function to provide impulses in the line circuit. If relay E remains down, for any reason, for too long a period, then relay OC is dropped out and the control circuit including its lower front contact, which controls the PC and NC relays, is opened so that the system is restored to normal.

Relay CF is the station start relay, this relay being picked up when the system is initiated from a field station and remains up throughout the following cycle, being dropped during the clearing out period at the end of the cycle. It is not believed necessary to illustrate the control of relay CF, it being sufficient to understand that it is picked up when relay F is dropped in response to a station opening the line, the circuit for relay CF including back contact 15 of relay F.

Message receiving relays PM and NM register the positive and negative indication impulses received by relay R during the time spaces between impulses applied to the line from the control office. These message relays, when picked up, are stuck up until the messages which they have received are executed, by energizing indication receiving relays 1IR and 2IR in the manner which will be described in detail in connection with the description relating to the transmission and reception of indications.

Field station equipment.—The field station illustrated in Figs. 2A and 2B is typical of all stations of the system and may be adapted for use at any location by merely connecting certain code jumpers to arrange for the desired codes, but for convenience in the description it is assumed that this is the first station on the line by reason of the distinctive exponents employed.

The track switch, switch machine, switch machine control relay, signals and signal control relays are not shown on the drawings, since the method of controlling the track switch and signals by polar impulses applied to the line circuit is immaterial to an understanding of the present invention and may be the same as disclosed in the above mentioned Judge et al., Patent No. 2,682,544 granted June 1, 1937.

The track section is likewise not illustrated, but for the purpose of illustrating the transmission of indications, relay WP¹ is shown in Fig. 2B, this being the relay which repeats the position of the associated track switch by opening its neutral front contact when the track switch is unlocked, by closing the neutral front contact and positioning the polar contact to the left when the switch is in its normal locked position, and by closing the neutral front contact and positioning its polar contact to the right when the switch is in the reverse locked position.

The communication part of the system, to which the present invention is more closely related, includes a line relay F¹ of the three-position biased-to-neutral polar type, together with its quick acting repeating neutral relay FP¹ and slow acting relays SA¹ and SB¹, all for a purpose similar to corresponding relays in the control office.

The field station includes a bank of stepping relays comprising half-step relay VP¹ and stepping relays 1V¹, 2V¹, 3V¹ and EX¹, the latter being the relay which is picked up on the last step for executing the controls received at the associated station.

Compensating resistance CR¹ is employed for the purpose of compensating for the line beyond a sending station, when this sending station conditions the line in towards the control office for starting the system and for providing the lockout feature.

Change relay CH¹ is provided to register a change in any of the traffic controlling devices in the station or a change in the position of the track relay, so that the system will be initiated for the transmission of indications. The operating circuits of this change relay have been omitted, but it will be understood that it responds by means of a momentary deenergization of its stick circuit, the manner in which this is accomplished being disclosed in Patent No. 1,852,402.

Lockout relay LO¹ is provided to determine when this field station is to transmit its indications. Whenever the lockout relay is picked up during a cycle for permitting the associated field station to transmit, the indication pulser is inserted in the line, so that polar impulses may be applied thereto from a source of current for the transmission of indication codes such source of current being illustrated as battery LB¹. It will of course be understood that this source of current can be a motor generator set or any desired type of converter. The lockout arrangement provided, by means of which relay LO¹ is only effective when the illustrated station obtains access to the line circuit for the transmission of indications, is not shown since this feature is immaterial to an understanding of the present invention and may be as shown in the Hailes application, Ser. No. 82,711, filed June 1, 1936, now Patent No. 2,114,001 granted April 12, 1938.

Impulse relay E¹ cooperates with relay FP¹ for the purpose of applying the indication impulses to the line circuit at the proper times, as will be explained in detail. Relay PB¹ and relay PT¹ cooperate in providing the locking feature and in the following description it will be merely pointed out how these relays are controlled to initiate a cycle of operations from a transmitting field station. Indication transmitting relays PZ¹ and NZ¹ provide the positive and negative impulses for the indication code transmission, the functioning of these relays being explained in detail later.

Operation

The system of the present invention is normally at rest and it may be initiated into a cycle of operations from the control office, when new controls are to be transmitted, or from a field station when new indications are to be transmitted. In the event that new controls and new indications are ready to be transmitted at the same time at the beginning of a cycle, then the duplex feature of the system permits this transmission simultaneously during the same cycle.

For convenience in describing the operation of the present system, an operating cycle will be divided into a number of impulse periods separated by time spaces and these impulse periods will be referred to as "on" periods of the cycle, with the time spaces being referred to as "off" periods of the cycle. These "on" and "off" periods refer to the impulsing of the line by the apparatus in the control office and from energy supplied from the battery in the control office.

Normal conditions.—The line circuit is normally energized over a circuit which may be traced from the (+) terminal of battery LB in the

- control office, winding of relay F, back contact 16 of relay PC, front contact 17 of relay NC, line conductor 12, through the tie at the end station illustrated by the dotted line in the upper right hand portion of Fig. 2A, line conductor 119, back contact 116 of relay PB¹, back contact 117 of relay FP¹, back contact 118 of relay E¹, back contact 119 of relay E¹, back contact 115 of relay FP¹, winding of relay F¹, line conductor 10, front contact 18 of relay NC and back contact 19 of relay PC, to the (—) terminal of battery LB. It will be understood that the line circuit includes relays and contacts at other field stations in the system, similar to those traced for the field station illustrated in Fig. 2A.
- Relay NC is normally energized over a circuit extending from (+), back contact 23 of relay SB, back contact 24 of relay CF, back contact 25 of relay C and winding of relay NC, to (—).
- 20 The above described energizing circuit for the two-wire line circuit effects the energization of relays F, F¹ and the line relays of all other stations connected to this line circuit. Since a (—) potential is applied to line conductor 19, it will be assumed current flow effected by this polarity of energization of the line operates the polar contacts of the station line relays to the left, as illustrated by relay F¹ of Fig. 2A.
- At the field station, relay PT¹ is normally energized over a circuit extending from (+), contact 111 of relay F¹ in its left hand position, back contact 112 of relay SB¹ and winding of relay PT¹, to (—). All other relays illustrated in the present drawings are normally deenergized, except relay CH¹ of Fig. 2A, which relay is responsive to a change in conditions at the associated field station for initiating the system for the transmission of indications.
- 40 *Manual start.*—For the purpose of considering the operation of the present system for the transmission of controls, it will be assumed that the station illustrated in Figs. 2A and 2B is selected in response to the operation of the starting button STB of Fig. 1A. It will furthermore be assumed that switch machine lever SML is positioned to the right for controlling the operation of the track switch (not shown) at the illustrated station to its normal locked position.
- The actuation of button STB effects the picking up of relays C and CD, after which a circuit is closed for picking up relay OC which extends from (+), back contact 23 of relay SB, back contact 24 of relay CF, front contact 25 of relay C and winding of relay OC, to (—). The opening 50 of back contact 25 of relay C deenergizes the above described normal energizing circuit for relay NC, so that this relay is released.
- A circuit is now closed for picking up relay PC which extends from (+), back contact 26 of relay E, front contact 27 of relay OC, front contact 28 of relay C, back contacts 29, 30 and 31 of relays 3V, 2V and 1V and winding of relay PC, to (—). The release of relay NC opens the above described energizing circuit for the line 60 and the picking up of relay PC again energizes the line circuit, but in this instance the current flow over the line circuit is of positive polarity and flows in a reversed direction from that above described. In other words, the (—) energization of the line circuit is changed to a (+) energization and this marks the beginning of the conditioning "on" period. This effects the momentary release of relay F in the control office and the immediate reenergization of this 70 relay. This reversal of line circuit current also

swings the polar contacts of the F relays at the field stations from their left to their right hand positions.

Relay FP in the control office is energized over a circuit extending from (+), front contact 32 of relay PC, front contact 33 of relay F and winding of relay FP, to (—). Relay SA is energized over a circuit extending from (+), front contact 32 of relay PC, front contact 34 of relay FP and winding of relay SA, to (—). Relay SB is energized over a circuit extending from (+), front contact 35 of relay SA and winding of relay SB, to (—). A substitute circuit for that closed at front contact 32 of relay PC is now closed at front contact 36 of relay SB, for energizing relay SA during the "on" periods of the following cycle, irrespective of whether relay PC is picked up or not and for causing relay FP to repeat the operations of relay F.

The picking up of relay SB effects the energization of relay VP, over a circuit not shown and relay VP closes a first stick circuit for itself. The picking up of relay VP closes a circuit for energizing relay E which extends from (+), front contact 37 of relay SB, back contacts 38, 39 and 40 of relays 3V, 2V and 1V, front contact 41 of relay VP and winding of relay E, to (—). The picking up of relay E opens the above described circuit for relay PC at back contact 26, which allows relay PC to release and deenergize the line circuit to mark the end of the conditioning "on" period and the beginning of the first "off" period.

The deenergization of the line at the beginning of the first "off" period effects the deenergization of the F relays and relay FP is deenergized because of open front contact 33 of relay F. A second stick circuit is closed for maintaining relay VP energized, a pick up circuit is closed for picking up relay 1V and the picking up of relay 1V establishes a stick circuit for itself, which circuits are not shown. The picking up of relay 1V opens the above described energizing circuit for relay E at back contact 40, so that relay E releases and closes a pick up circuit for relay PC extending from (+), back contact 26 of relay E, front contact 27 of relay OC, front contact 28 of relay C, back contacts 29 and 30 of relays 3V and 2V, front contact 31 of relay 1V, front contact 42 of relay CD, jumper 13 in its full line position and winding of relay PC, to (—). The picking up of relay PC applies a (+) energization to the line circuit to mark the end of the first "off" period and the beginning of the first "on" period.

Relays F and FP respond as before and the picking up of relay FP effects the release of relay VP. A circuit is now closed for picking up relay E which extends from (+), front contact 37 of relay SB, back contact 38 of relay 3V, back contact 39 of relay 2V, front contact 40 of relay 1V, back contact 41 of relay VP and winding of relay E, to (—). Relay PC is now released because the above described energizing circuit for this relay is open at back contact 26 of relay E. This deenergizes the line to mark the end of the first "on" period and the beginning of the second "off" period.

Relays F and FP are released as before and relay 2V is picked up and stuck up. The picking up of relay 2V effects the release of relay E because of open back contact 39 and the release of relay E closes a pick up circuit for relay NC which extends from (+), back contact 26 of relay E, front contacts 27 and 28 of relays OC and C, back contact 29 of relay 3V, front con-

tact 30 of relay 2V, front contact 43 of relay CD, jumper 14 in its full line position and winding of relay NC, to (-). The picking up of relay NC applies a (-) energization to the line circuit to mark the end of the second "off" period and the beginning of the second "on" period.

5 Relays F and FP are picked up as before and relay VP is picked up and stuck up in response to the picking up of relay FP. Relay E is now picked up over a circuit extending from (+), front contact 37 of relay SB, back contact 38 of relay 3V, front contact 39 of relay 2V, front contact 41 of relay VP and winding of relay E, to (-). The opening of back contact 26 of relay E effects the deenergization of relay NC, which in turn deenergizes the line circuit to mark the end of the second "on" period and the beginning of the third "off" period.

10 Relays F and FP are released as before, a second stick circuit is closed for maintaining relay VP energized and relay 3V is picked up. Relay E is now released because of open back contact 38 and a circuit is closed for picking up relay PC which extends from (+), back contact 25 15 of relay E, front contacts 27 and 28 of relays OC and C, front contact 29 of relay 3V, front contact 44 of relay CD, lever SML in its right hand position and winding of relay PC, to (-). Relay PC applies a (+) energization to the line circuit to mark the end of the third "off" period and the beginning of the third "on" period.

20 Relays F and FP are picked up as before and relay VP is released. A circuit is now closed for picking up relay E which extends from (+), front contact 37 of relay SB, front contact 38 of relay 3V, back contact 41 of relay VP and winding of relay E, to (-). The opening of back contact 26 of relay E deenergizes the above described circuit for relay PC, which effects the 25 release of relay PC for deenergizing the line circuit to mark the end of the third "on" period and the beginning of the clearing out "off" period.

25 Relays F and FP are released as before, but since there is no other stepping relay to be picked up to change the condition of relay E, this latter relay remains energized and the line remains deenergized, with relays F and FP down, for a sufficiently long interval to release relay SA, because of open front contact 34 of relay FP. The release of relay SA effects the release of relay SB because of open front contact 35. The stick circuits for the stepping relays are deenergized by the release of relay SB and these stepping relays are released at this point in the cycle. The opening of front contact 37 of relay SB also effects the deenergization of relay E. Furthermore, the C and CD relays are deenergized by the release of relay SB.

30 Relay NC is now picked up over the previously described normal energizing circuit, which effects the normal (-) energization of the line circuit for picking up relay F and for positioning the line relays at the stations to the left.

35 It will be understood that relay SA is not released during the above described impulsion of the line circuit, because front contact 34 of relay FP does not remain open for a sufficiently long period of time during this impulsion to allow relay SA to release. Relay OC is likewise maintained in its picked up position during the impulsion of the line circuit, because of a stick circuit extending from (+), front contact 23 of relay SB, front contact 45 of relay E, front contact 46 and winding of relay OC, to (-). When 40 relay SB releases during the clearing out period,

the opening of its front contact 23 effects the deenergization of relay OC for a time sufficient to allow it to release.

45 It will thus be seen that, in the event that impulsion is interfered with during the cycle, so that the system stops during an "on" period, relay E will remain down long enough to effect the release of relay OC, which in turn opens front contact 27 to effect the release of the PC or NC relay, so that the line is deenergized for clearing out the cycle. In the event that the system stops in an "off" period, then the line is deenergized sufficiently long for relay FP to remain down sufficiently long to effect the release of relay SA, so that the system is cleared out.

15

50 *Polarity selection of impulses.*—In the above example, it has been pointed out how relay PC is picked up during the conditioning "on" period, the first "on" period and the third "on" period and how relay NC is picked up during the second "on" period. Relay PC is always picked up during the conditioning "on" period for energizing the line with a (+) impulse and the succeeding impulses are rendered (+) or (-) in accordance with the positions of the code jumpers and the control levers associated with relay CD.

55 In the event that jumper 13 is in its alternate dotted line position, then relay NC is picked up during the first "off" period for making the first "on" impulse (-) instead of (+), as in the above example. The same applies to jumper 14, which is selected when relay 2V is picked up during the second "off" period for selectively energizing relay PC or NC to render the second "on" impulse (+) or (-). This operation occurs on each 60 step of the cycle for determining the code to be applied to the line circuit, by selecting the PC or NC relay during "off" periods in readiness for energizing the line with a (+) or (-) impulse during succeeding "on" periods, in accordance with this selection.

65 It will be understood that this arrangement may be extended for as many steps as desired, with stepping relays being picked up during the "off" periods and the VP relay being shifted from one position to another during the "on" periods. The stepping relay operation at the field stations is the same as in the control office, these station stepping relays being picked up and released in approximate synchronism with 70 corresponding relays in the office. The circuit arrangement for the stepping relay operation at the station is merely indicated by dotted line 120.

75 It will be noted that the pick up circuit for relay FP¹ extends through front contact 113 of relay LO¹ or front contact 114 of relay SO¹, so that the operation of relay FP¹ at a field station is dependent on a station being selected for controls by its SO relay being picked up, or that the station is transmitting indications by reason 80 of its LO relay being picked up. The actuation of the contacts of relay F¹ to the right during the conditioning "on" period effects the picking up of relay SO¹, over a circuit not shown, after which relay FP¹ is energized over a circuit extending from (+), contact 111 of relay F¹ in its right hand dotted position, back contact 113 of relay LO¹, front contact 114 of relay SO¹, back contact 123 of relay E¹ and winding of relay FP¹, to (-). A stick circuit for relay FP¹ is 85 established at its front contact 124, which circuit bridges back contact 123 of relay E¹ and is for the purpose of maintaining relay FP¹ energized until relay F¹ is deenergized, irrespective of the position of relay E¹.

76

Relay SA¹ is picked up during the conditioning "on" period, over a circuit first closed at contact 111 of relay F¹ in its right hand dotted position and thereafter closed at front contact 125 of relay FP¹. Relay SA¹ closes a circuit for picking up relay SB¹ which extends from (+), front contact 126 of relay SA¹, back contact 127 of relay PB¹ and winding of relay SB¹, to (-).

Relay VP¹ is picked up during the conditioning "on" period, is released during the first "on" period, is picked up during the second "on" period and is released during the third "on" period, in approximate synchronism with the VP relay in the office.

15 The picking up of relay VP¹ during the conditioning "on" period closes a circuit for picking up relay E¹ which extends from (+), front contact 128 of relay SB¹, back contacts 129, 130 and 131 of relays 3V¹, 2V¹ and 1V¹, front contact 132 of relay VP¹ and winding of relay E¹, to (-). When relay 1V¹ is picked up during the first "off" period, the above described circuit for relay E¹ is opened at back contact 131 and relay E¹ is released. When relay VP¹ releases during the first 25 "on" period, the circuit for relay E¹ is again completed by way of front contact 131 of relay 1V¹ and back contact 132 of relay VP¹.

The picking up of relay 2V¹ in the second "off" period opens the energizing circuit for relay E¹ 30 at back contact 130. The picking up of relay VP¹ during the second "on" period completes the energizing circuit for relay E¹ at front contact 132. The release of relay VP¹ during the third "on" period completes the energizing circuit for relay E¹, by way of front contact 129 of relay 3V¹ and back contact 132 of relay VP¹.

When relay FP¹ remains down for an extra long interval during the clearing out period, the continued open condition of front contact 125 effects the release of relay SA¹ and the open condition of contact 126 effects the release of relay SB¹. Relays SO¹, E¹ and the stepping relays are all deenergized by the release of relay SB¹.

The picking up of relay FP¹ during the conditioning "on" period changes the path of the line circuit, from that previously described, to one which may be traced from line conductor 10, winding of relay F¹, front contacts 115 and 117 of relay FP¹ and back contact 116 of relay PB¹. This change in the line circuit path is for no purpose during a control cycle, but its function will be described in connection with an indication cycle. Furthermore, relay PT¹ is released during the conditioning "on" period, by the opening of back contact 112 of relay SB¹ and relay PT¹ is not again reenergized until relay SB¹ is released during the clearing out period and relay F¹ closes contact 111 in its left hand position during the normal period. The purpose of relay PT¹ will be described in connection with the starting of an indication cycle.

Control code.—When controls are transmitted, field stations are selected one at a time in accordance with the combination of (+) and (-) impulses applied to the line circuit during the station selection part of the cycle, which in the present embodiment is assumed to be during the first and second "on" periods, as determined by the positions of jumpers 13 and 14 of Fig. 1A. The circuits for the field stations are similar, the difference being in the positions of the station code jumpers (not shown) which serve to condition selecting circuits for the SO relays, so that only one of these relays will remain energized after the receipt of the last station selecting code

impulse. As above mentioned, it is believed unnecessary to illustrate the detailed arrangement for accomplishing station selection.

After the proper combination is applied to the line circuit for selecting the desired station, then the following impulses in the line circuit are for the purpose of controlling switch machines, signals and the like, in accordance with the position of the control levers in the office associated with the selected station. With lever SML in its right hand position, a (+) impulse is applied to the line circuit during the third "on" and the actuation of contact 133 of relay F¹ to the right, in response to this impulse, is effective to control a switch machine control relay which may be connected to the No. 3 (+) control channel, the circuit being traced from (+), front contact 134 of relay SO¹, back contact 135 of relay E¹, front contact 136 of relay FP¹, contact 133 of relay FP¹ in its right hand dotted position, front contact 137 of relay 3V¹ and by way of the No. 3 channel conductor, to the control relay connected to this conductor. In the event that lever SML is in its left hand dotted position, then the third "on" impulse is (-) for positioning contact 133 of relay F¹ to the left, which selects the No. 3 (-) channel conductor, for controlling the switch machine control relay to its opposite position.

In a similar manner, any number of additional steps may be provided for transmitting additional controls to the selected field station for governing signals and such other devices as may be employed. It will be noted that the (+) and (-) control channel circuits can only be energized at a station where relay SO¹ has its front contact 35 134 closed, which effects the selection of the desired station, so that these control channel conductors cannot be energized during a cycle in which the SO relays are dropped out. The purpose of back contact 138 of relay SB¹ is to provide an energizing circuit for picking up relay SO¹ when relay F¹ swings to the right, this circuit extending through back contacts 137, 139 and 140 of relays 3V¹, 2V¹ and 1V¹.

An executing bus has been illustrated, which is for the purpose of executing the composite control code at a selected station, after this code has been registered and the system is going through its clearing out period. This circuit extends from (+), front contact 141 of relay SO¹ (up until relay SB¹ releases), back contact 142 of relay SA¹ (down for an appreciable interval of time before relay SB¹ releases) and front contact 143 of relay EX¹, this latter relay being released after the release of relay SB¹, the same as the stepping relays.

Transmission of indications.—Although the system is of the coded duplex type, arranged for the transmission of indications from any station to the control office during the same cycle that controls are transmitted to the same station or to some other station, it will first be explained how the system operates for the transmission of indications alone on a separate operating cycle. The duplex feature of the system will be explained later on in the description. It will now be assumed that the station illustrated in Figs. 2A and 2B has indications ready for transmission to the control office.

Automatic start.—A change in the condition of the track section or a change in the condition of the traffic controlling devices at the illustrated station effect the deenergization of relay CH¹, which closes a circuit for picking up relay PB¹ extending from (+), back contact 144 of relay SB¹, 75

back contact 136 of relay FP¹, contact 133 of relay F¹ in its left hand position, back contacts 145, 146 and 147 of relays 3V¹, 2V¹ and 1V¹, back contact 148 of relay CH¹, back contact 149 of relay 5 LO¹, front contact 150 of relay PT¹, back contact 151 of relay FP¹ and winding of relay PB¹, to (—). Relay PB¹ closes a stick circuit for itself extending from (+) front contact 152 of relay PT¹, front contact 153 and winding of relay 10 PB¹, to (—).

The picking up of relay PB¹ opens the above described normally energized line circuit at back contact 116, which effects the release of relays F¹, F and all other line relays at other stations 15 in the system. The opening of contact 111 of relay F¹ deenergizes relay PT¹ and, after a comparatively long interval of time, relay PT¹ releases.

The release of relay F in the control office and the consequent closing of its back contact 15 is effective to pick up relay CF¹. Relay OC is now picked up over a circuit extending from (+), back contact 23 of relay SB, front contact 24 of relay CF and winding of relay OC, to (—). The opening of back contact 24 of relay CF deenergizes 25 relay NC, to remove the (—) energization from the line circuit and the picking up of relays CF and OC close a circuit for picking up relay PC, to apply a (+) energization to the line circuit. The pick up circuit for relay PC extends from 30 (+), back contact 26 of relay E, front contact 27 of relay OC, back contact 28 of relay C, front contact 47 of relay CF, back contact 48 of relay 1V and winding of relay PC, to (—). The line is closed at the station at front contact 116 of relay PB¹, back contact 186 of relay PT¹, back contact 187 of relay SB¹ and resistance CR¹.

This (+) energization of the line circuit picks up relay F in the control office and positions relay F¹ at the field station to the right. This (+) energization is held on the line for a comparatively long interval of time, during which conditioning takes place at the office and at the stations in the same manner described in connection with a control cycle. In this instance, the actuation of contact 133 of relay F¹ to the right effects the picking up of relay SO¹ as before, but during the succeeding cycle relay SO¹ is released because the impulses applied to the line circuit are all (—) (for a reason to be described), which makes up a phantom code ineffective to select any field station. Contact 133 to the right also picks up relay LO¹ by way of back contact 153 of relay 45 1V¹, by means of a circuit not shown, but which circuit is dependent on relay PB¹ being picked up, 50 due to the initiation of the system from the illustrated field station.

As previously mentioned, the lockout feature of the present system is not shown, since this feature is immaterial to an understanding of the 55 present invention and since it may be the same as disclosed in the above mentioned Hailes application. It need only be understood that relay LO¹ at the illustrated station is picked up and stuck up throughout the following cycle, when indications are initiated at the station. Furthermore, when indications are simultaneously initiated at two or more stations, the LO relay at the station nearest the control office will remain up during the succeeding cycle, while the other LO relays which were picked up will be released during the conditioning "on" period.

During an indication cycle, the line circuit is 60 impaled with a series of (—) impulses, the stepping relay banks and the E relays being operated in the same manner described in connection with

a control cycle. Relay NC is selected and energized each time back contact 26 of relay E closes, over a circuit extending through front contact 27 of relay OC, back contact 28 of relay C, front contact 47 of relay CF and front contact 48 of relay 1V, the latter relay being picked up during the first "off" period following the conditioning "on" period, during which the line was energized with a (+) impulse.

Registration of a field station.—Recalling that the two wire line circuit is impaled with a series of (—) impulses from battery LB in the control office, by the intermittent energization and deenergization of relay NC, controlled by relay E, which is in turn controlled by the response of the stepping relay bank to these impulses, it will now be explained how the transmitting field station inserts an indication impulser into the line circuit, during the above described "off" periods, for providing indication codes made up of (+), (—) or zero impulses in the line.

At the particular station (assumed to be the station illustrated in Figs. 2A and 2B) having indications to transmit, lockout relay LO¹ is maintained energized throughout the cycle. Recalling that the stepping relay bank in the control office operates in synchronism with the stepping relay banks at the field stations, it will be noted that the closure of front contacts 154 and 155 (see Fig. 2B) of relay LO¹ permits the energization or deenergization of relays NZ¹ and PZ¹, in accordance with a code combination made up by the positions of the indication code jumpers and the positions of indication transmitting contacts on certain relays, such as relay WP¹.

When relay SB¹ is picked up during the conditioning "on" period, it maintains the circuit of relay PT¹ open at back contact 112, so that relay PT¹ remains down during the following cycle. The opening of front contact 152 of relay PT¹ 40 opens the stick circuit of relay PB¹, this latter relay having its stick circuit maintained closed also by way of front contact 156 of relay LO¹ and back contact 157 of relay SO¹, for a purpose which relates to the lockout feature. With the stick circuit of relay PB¹ open at front contact 152 of relay PT¹ and at back contact 157 of relay SO¹, relay PB¹ is released because its pick up circuit is open at front contact 150 of relay PT¹. This release of relay PB¹ re-establishes the line circuit 45 through all stations to the end of the line, as will be noted by tracing the circuit for line wire 10 through relay F¹, back contacts 115, 119, 118 and 117 of relays FP¹ and E¹ and back contact 116 of relay PB¹, to line conductor 110, which line 50 conductor is tied to the return conductor 12 at the end station.

The line circuit is impaled with the indication code impulses during the "off" periods, while relay FP¹ is down and relay E¹ is up. At this time, 60 relay F¹ is short-circuited by means of back contact 158 of relay FP¹ and front contact 159 of relay E¹, so that the indication impulses applied to the line circuit are ineffective to operate the line relay which controls stepping. At all other stations at which stepping takes place, for example, during a duplex cycle when controls are being transmitted, a similar circuit is effective to short-circuit the line relays at these stations to prevent stepping during the transmission of indication 65 impulses. Likewise, in the control office, relay E is picked up and relay F is released during these "off" periods, so that a bridge is placed across the line in the control office extending from conductor 70 12, front contacts 49 of relay E, back contacts 55 75

and 51 of relays NM and PM, winding of relay R, back contact 52 of relay F, back contacts 53 and 54 of relays PC and NC, to conductor 10. It will thus be seen that, during the "off" periods, relay 5 R in the control office is momentarily substituted for relay F in the line.

In the example chosen for illustration, the first "off" period is not impaled, in other words, the indication code provided during the first "off" 10 period is a zero impulse. This is because code jumpers 160 and 161 (Fig. 2B) are both disconnected from (+), so that neither relay NZ¹ nor relay PZ¹ is picked up and the line is not energized from the station during the first "off" period. 15 During the first "on" period, a circuit is closed for picking up relay PZ¹ which extends from (+), jumper 162, front contact 163 of relay 1V¹, back contacts 164 and 165 of relays 2V¹ and 3V¹, front contact 166 of relay LO¹, front contact 168 of relay 20 FP¹ and winding of relay PZ¹, to (-). When relay E¹ is picked up during the first "on" period, a first stick circuit is closed for relay PZ¹ extending from (+), front contact 167 of relay LO¹, front contact 168 of relay PZ¹, front contact 169 25 of relay E¹ and winding of relay PZ¹, to (-).

When relay FP¹ releases during the second "off" period, a second stick circuit is closed for relay PZ¹, by reason of back contact 166 bridging front contact 169. It will thus be seen that, when relay 30 PZ¹ is picked up during the first "on" period, it is stuck up throughout the next (second) "off" period and until relay FP¹ is picked up in the next succeeding (second) "on" period.

With relay PZ¹ picked up throughout the second "off" period, a (+) impulse is applied to the line circuit during the interval between the dropping of relay FP¹ and the dropping of relay E¹, over a circuit which may be traced from the (+) terminal of battery LB¹, back contact 170 of relay 35 NZ¹, front contact 171 of relay PZ¹, front contact 172 of relay E¹, back contact 173 of relay FP¹, back contact 174 of relay PB¹, line conductor 110, through the tie at the end station, line conductor 172, front contact 49 of relay E, back contacts 50 40 and 51 of relays NM and PM, winding of relay R, back contact 52 of relay F, back contacts 53 and 54 of relays PC and NC, line conductor 10, back contact 158 of relay FP¹, front contact 159 of relay E¹, back contact 115 of relay FP¹, front contact 119 of relay E¹, front contact 172 of relay SB¹, front contact 173 of relay PZ, back contact 174 of relay NZ¹ and front contact 175 of relay LO¹, to the (-) terminal of battery LB¹.

The above described circuit, including the line 55 conductors, extends through other stations connected to the system and in order to provide a path through these stations, back contact 176 of relay LO¹ is provided, it being understood that similar back contacts are provided on the lockout relays 60 at the other stations. The reason for this will be apparent when considering that the FP, E and SB relays at the other stations operate in approximate synchronism with those at the transmitting station, so that the path extending through back 65 contacts of the FP¹ relay and front contacts of the E¹ relay at the transmitting station, by way of back contact 116 of relay PB¹, will find a path over conductor 110 which is similar to that extending through back contact 158, front contact 159, back 70 contact 115, front contact 119, front contact 172, back contact 176, front contact 118, back contact 117 and back contact 116, to the line conductor extending toward the end of the system.

From the above description it will be observed 75 that the contact arrangement shown on relays FP¹

and E¹, in the upper left hand portion of Fig. 2A, connects and disconnects the indication impulser to and from the line circuit during the "off" periods and that the contact arrangement, including contact 176 of relay LO¹, closes the line circuit around contacts 170, 171, 173 and 174 of relays PZ and NZ at the stations not sending indication impulses.

The (+) impulse applied to the line circuit, during the second "off" period, is effective to position relay R in the control office to the right for picking up relay PM, by means of a circuit closed at contact 55 of relay R in its right hand dotted position. This impulse is only momentary, it being terminated by the picking up of relay PM 15 and the consequent opening of its back contact 51, as well as the releasing of relay E¹ at the transmitting station and the consequent opening of the impulser circuit at front contacts 118 and 119. A stick circuit is provided for relay PM which extends from (+), front contact 56 of relay SA, back contact 57 of relay F, front contact 58 and winding of relay PM, to (-). This stick circuit is maintained as long as relay F is down and as long as relay E is down, because of back contact 59 of relay E bridging back contact 57 of relay F. Relay PM is therefore stuck up throughout the second "on" period, until relay E picks up and opens its back contact 59, whereupon relay PM is released.

It will be understood that a (-) impulse may be applied to the line circuit during the second "off" period, by connecting jumper 162 in its dotted line position and jumper 177 in its full line position, so that relay PZ¹ will not pick up and relay NZ¹ will pick up. The method of making this impulse (-) will be understood in connection with the transmission during the third "off" period, later to be explained.

Execution of the indication codes transmitted 40 during the "off" periods is effected during the following "on" periods. In the above example, a zero impulse was transmitted during the first "off" period, so that neither relay PM nor NM was picked up. This condition is executed while relay E is down, by closing a circuit to the first zero indication channel extending from (+), front contact 60 of relay CF, back contacts 61, 62 and 63 of relays PM, NM and E, back contacts 64 and 65 of relays 3V and 2V and front contact 66 of relay 1V, to the first zero indication channel 67, which channel connects to pilot relay 2PT for operation in the same manner later to be described in connection with indication relays 1IR and 2IR of Fig. 1B.

The (+) indication impulse applied to the line circuit during the second "off" period, which picked up relay PM, causes the second (+) indication channel conductor 68 to be energized, when execution takes place, by means of a circuit 60 extending from (+), front contact 69 of relay CF, front contact 70 of relay PM, back contacts 71 and 72 of relays NM and E, back contact 73 of relay 3V and front contact 74 of relay 2V, to channel conductor 68, for operating pilot relays 65 3PT and 4PT in a manner analogous to the operation of relays 1IR and 2IR later to be explained.

Although not illustrated, it will be readily understood that two pilot relays provided for each step and operated in response to any one of the 70 three code combinations per step, may be used to select any one of eight station relays for the two steps, the ninth possible code combination being a phantom code not used, due to the fact that when controls alone are transmitted over the sys- 75

tem, the indication code, comprising a zero impulse at each step, is inherently transmitted. Thus, relay 8ST is assumed to correspond to the illustrated field station and to be picked up in response to the above described indication code transmitted in accordance with the positions of jumpers 160, 161, 162 and 177, to register or identify in the control office, that the field station of Figs. 2A and 2B is the transmitting station.

10 *Transmission of indications.*—Relay WP¹ of Fig. 2B has been provided to illustrate how a choice of one out of three indications may be transmitted at a particular step of the cycle and this step in the present embodiment is assumed to be the third "off" period, as selected by the picking up of relay 2V¹ during the second "off" period and completed by the picking up of relay FP during the second "on" period.

With relay WP¹ in the illustrated position, a circuit is closed for picking up relay NZ¹ during the second "on" period extending from (+), front contact 178 of relay WP¹, polar contact 179 of relay WP¹ in its left hand position, front contact 180 of relay 2V¹, back contact 181 of relay 3V¹, front contact 184 of relay LO¹, front contact 182 of relay FP¹ and winding of relay NZ¹, to (—).

Relay NZ¹ is stuck up, as long as relay E¹ is picked up during the third "off" period, over a circuit extending from (+), front contact 183 of relay LO¹, front contact 184 of relay NZ¹, front contact 185 of relay E¹ and winding of relay NZ¹, to (—). The release of relay FP¹ completes the stick circuit for relay NZ¹ at back contact 182 before relay E¹ releases, so that relay NZ¹ is stuck up until relay FP¹ is picked up during the third "on" period. This means that relay NZ¹ will be maintained in its picked up position throughout the third "off" period and released in the next (third) "on" period, in readiness for the next selection.

With relay NZ¹ up throughout the third "on" period, a (—) impulse is momentarily applied to the line circuit over the previously described circuit, but which now extends through front contacts 178 and 174 of relay NZ¹, and back contacts 171 and 173 of relay PZ¹.

This (—) indication impulse, applied to the line circuit during the third "off" period, is effective to position relay R to the left for picking up relay NM over a circuit extending through contact 55 of relay R in its left hand dotted position. Relay NM immediately opens the line circuit at back contact 50, but establishes a stick circuit for itself before contact 55 opens, which stick circuit extends from (+), front contact 56 of relay SA, back contact 57 of relay F, front contact 75 and winding of relay NM, to (—). Contact 57 is bridged by back contact 59 of relay E, to maintain relay NM stuck up until relay E is picked up during the third "on" period.

The third indication code is executed during the third "on" period by closing a circuit extending from (+), front contact 76 of relay CF, back contact 77 of relay PM, front contact 78 of relay NM, back contact 79 of relay E, front contact 80 of relay 3V, front contact 81 of relay 8ST, lower winding of relay 1IR and lower winding of relay 2IR, to (—). As indicated by the arrows associated with the IR relays, current through the lower windings of relays 1IR and 2IR positions the polar contacts of these relays to the left, for closing a circuit for lighting lamp NL, extending from (+), contact 82 of relay 2IR in its left hand position, contact 83 of relay 1IR in its left hand position and lamp NL, to (—). The lighting of

lamp NL is an indication that relay WP¹ is repeating the associated track switch in its normal locked position.

In the event that contact 179 of relay WP¹ is in its reverse dotted line position, then relay PZ¹ would be picked up during the second "on" period, for applying a (+) indication impulse to the line circuit during the third "off" period, which would be effective to pick up relay PM and leave relay NM down. When this condition is executed, a circuit is closed through front contacts 69 and 70 of relays CF and PM, back contacts 71 and 72 of relays NM and E, front contact 73 of relay 3V, front contact 84 of relay 8ST, upper winding of relays 1IR and lower winding of relay 2IR in series, to (—). The arrows associated with these windings indicate that polar contact 83 of relay 1IR is positioned to the right and polar contact 82 of relay 2IR is positioned to the left, which is effective to close a circuit for lighting lamp RL, as an indication that relay WP¹ is in its reverse switch indicating position.

In the event that neutral contact 178 of relay WP¹ is open, then neither relay PZ¹ nor NZ¹ will be picked up, so that a zero indication impulse is transmitted during the third "off" period, which is effective to leave relays PM and NM both down during the third "on" period, when this condition is executed. A circuit is then completed by way of front contact 69 of relay CF, back contacts 61, 62 and 63 of relays PM, NM and E, front contact 64 of relay 3V, front contact 85 of relay 8ST and upper winding of relay 2IR, to (—). As illustrated by the arrow, this positions polar contact 82 to the right so that neither lamp is energized, as an indication that relay WP¹ is repeating the track switch in its unlocked condition.

From the above explanation of the operation of relays 1IR and 2IR, it is believed clear that similar relays provided for the first two steps may be operated in any one of three distinctive positions for each step in combination, so that the above mentioned station selection feature may be provided to a particular ST relay, in accordance with the station transmitting its indications.

Duplex operation.—It has been pointed out that control and indication cycles may each occur separately or simultaneously. The operations for a control cycle alone and the operations for an indication cycle alone have been described and it will now be briefly explained how the system operates when controls and indications are transmitted during the same cycle.

The actuation of a starting button in the control office can pick up its associated CD relay while the system is at rest and relay C will be picked up to mark the cycle as one during which controls are transmitted. A field station may initiate the system while it is at rest or during the initiation from the control office, so that its lockout relay may be picked up at the beginning of a cycle and maintained picked up throughout the succeeding cycle.

Therefore, under the condition that the system is initiated by the picking up of a CD relay in the office and a lockout relay at a field station at the beginning of a cycle, both controls and indications can be transmitted during this cycle. The polarity of each control impulse transmitted over the line during the above described "on" periods, is determined by the code jumper and lever connections selected by the energized CD relay. The identification or regis-

tration of a particular field station for the transmission of indications is determined by the particular lockout relay which is picked up, for effecting the transmission of (+), (-) or zero impulses during the "off" periods, as determined by the connections of the code jumpers at the field station. Furthermore, indications from the registered station are transmitted during the steps following station identification by providing (+), (-) or zero impulses during the "off" periods, all as previously described. Since controls are transmitted outward from the office and since indications are transmitted inward to the office by the separate and independent conditioning of the two-wire line circuit, these controls and indications can be simultaneously transmitted during the same cycle.

The clearing out operation for an indication cycle or for a duplex cycle is the same as previously described in connection with a control cycle and need not be repeated.

Although one specific embodiment of the invention has been shown, it is to be understood that various rearrangements may be made and still come within the scope of the invention.

Having thus described a centralized traffic controlling system as one embodiment of the present invention, it is desired to be understood that this form is selected to facilitate in the disclosure rather than to limit the number of forms which the invention may assume and it is further to be understood that various modifications, adaptations and alterations may be applied to the specific form shown to meet the requirements of practice without in any manner departing from the spirit or scope of the invention except as limited by the appended claims.

What I claim is:

1. In a remote control system; a control office and a field station connected by a line circuit; a first and a polar line relay in said office selectively and individually connected in series with said line circuit; means including said first line relay for impressing a series of control impulses on said line circuit for synchronously marking off a series of successive time spaced impulse periods at said office and at said station and for excluding said first line relay from said line circuit during each time space; means for connecting said polar line relay in series with said line circuit during the time spaces between the impulse periods; a code transmitter at said station; means for causing said code transmitter to apply a positive, a negative or a zero current impulse to said line circuit during each of the time spaces between said impulse periods, whereby codes are transmitted over said line circuit and said polar line relay is operated or left unoperated during each time space; and means controlled by said polar line relay for registering said codes.

2. In a remote control system; a control office and a field station connected by a line circuit; a first and a polar line relay in said office selectively and individually connected in series with said line circuit; means including said first line relay for impressing a series of distinctive polarity control impulses on said line circuit at said office for synchronously marking off a series of successive time spaced impulse periods at said office and at said station and for characterizing a control code by the polarity pattern of such series of impulses, said means also excluding said first line relay from said line circuit during each time space means controlled by said first line relay for connecting said polar line relay

in series with said line circuit during the time spaces between the impulse periods; a code transmitter at said station; means for causing said code transmitter to apply impulses of positive, negative, and zero current to said line circuit during the time spaces between said impulse periods, whereby codes are transmitted over said line circuit and said polar line relay is operated to a particular polar position or is left unoperated during each time space; and means controlled by said polar line relay for registering said codes.

3. In a remote control system; a control office and a field station connected by a line circuit; a first and a polar line relay in said office selectively and individually connected in series with said line circuit; means including said first line relay for impressing a series of distinctive polarity control impulses on said line circuit to form a polarity pattern to constitute a code and for synchronously marking off a series of successive time spaced impulse periods at said office and at said station, said means also excluding said first line relay from said line circuit during each time space; means controlled by said first line relay for connecting said polar line relay in series with said line circuit during the time spaces between the impulse periods; a code transmitter at said station; means for causing said code transmitter to apply positive, negative and zero current impulses to said line circuit during the time spaces between said impulse periods, whereby codes are transmitted over said line circuit and said polar line relay is left unoperated or is distinctively operated once during each time space thereby; means controlled by said polar line relay for registering said codes, and means controlled by said polar line relay for removing itself from said line circuit.

4. In a remote control system; a control office and a plurality of field stations connected by a line circuit; a first and a polar line relay in said office selectively connected in series with said line circuit; means including said first line relay for intermittently energizing said line circuit from a source of current in said office to synchronously mark off a series of successive time spaced impulse periods at said office and at said stations and for excluding said first line relay from said line circuit during each time space; means for connecting said polar line relay in said line circuit during the time spaces between said impulse periods; a code transmitter at each of said stations; means for causing the code transmitter at a transmitting station to insert itself in series with said line circuit and apply positive, negative and zero current impulses thereto during the time spaces between said impulse periods, whereby codes are transmitted over said line circuit and said polar line relay is operated or left unoperated for each impulse thereby; means controlled by said polar line relay for registering said codes; and means at each non-transmitting station for preventing the insertion of the associated code transmitter.

5. In a remote control system; a control office and a plurality of field stations connected by a line circuit; a first and a polar line relay in said office selectively connected in series with said line circuit; means including said first line relay for intermittently energizing said line circuit from a source of current in said office to synchronously mark off a series of successive time spaced impulse periods at said office and at said stations and for excluding said first line relay

from said line circuit during each time space; means for connecting said polar line relay to said line circuit during the time spaces between said impulse periods; a code transmitter at each of 5 said stations; means for causing the code transmitter at a transmitting station to insert itself in series with said line circuit and apply polar and zero current impulses thereto during the time spaces between said impulse periods, whereby 10 codes are transmitted over said line circuit and said polar line relay is reversibly operated or left unoperated during each time space thereby; means controlled by said polar line relay for registering said codes; and means at each non-transmitting station for preventing the insertion 15 of the associated code transmitter.

6. In a remote control system, a control office and a plurality of field stations connected by a line circuit; a first and a polar line relay in said 20 office selectively connected in series with said line circuit; means located wholly at said office and including said first line relay for intermittently energizing said line circuit from a source of current in said office to synchronously mark off a series of successive time spaced impulse periods at said office and at said stations; means for disconnecting said first line relay from and connecting said polar line relay to said line circuit during each time space between said impulse 25 periods; a code transmitter at each of said stations; means for causing the code transmitter at a transmitting station to intermittently insert itself in series with said line circuit and apply polar and zero current impulses thereto during 30 the time spaces between said impulse periods, whereby codes are transmitted over said line circuit and said polar line relay is intermittently reversibly operated or left unoperated thereby; means controlled by said polar line relay for 35 registering said codes; and means at each non-transmitting station for preventing the insertion of the associated code transmitter in said line circuit, whereby said line circuit is rendered continuous through all of said plurality of stations during both the impulse and the time space of an 40 impulse period.

7. In a remote control system; a control office and a plurality of field stations connected by a line circuit; a first line relay and a polarity responsive second line relay in said office selectively connected in series with said line circuit; a station line relay at each of said stations connected in series with said line circuit; means including 50 said first line relay for intermittently energizing said line circuit from a source of current in said office to synchronously mark off a series of successive time spaced impulse periods at said office and at said stations; means for disconnecting said first line relay from and connecting said 55 second line relay to said line circuit during the time spaces between said impulse periods; a code transmitter at each of said stations; means including the station line relay at a transmitting station for causing the code transmitter at that 60 station to insert itself in series with said line circuit and apply polar impulses thereto during the time spaces between said impulse periods, whereby codes are transmitted over said line circuit and said polarity responsive second line relay is reversibly operated thereby; means controlled by the operation of said polarity responsive second line relay for registering said codes; means at each non-transmitting station for preventing the insertion of the associated code 65 transmitter in said line circuit whereby said line 70 circuit

circuit is rendered continuous through all of said plurality of stations; and means for removing each station line relay from the line when a code transmitter is inserted in the line circuit at a transmitting station.

8. A communication system for transmitting control codes from an office to any one of a plurality of stations and for transmitting indication codes from any one of said stations to said office comprising, a single line circuit extending from 10 said office through all of said stations, a line relay at said office and a polar line relay at each of said stations included in series in said line circuit, a polar indication line relay at said office, means at said office for energizing said line circuit extending through all of said line relays by series of positive and negative polarity control impulses arranged in a polarity pattern to define a code, 15 step-by-step mechanism at said office and at each of said stations controlled solely by said impulses irrespective of their polarity, means at each field station controlled by the polar line relay at such station and the step-by-step mechanism at such station responsive to such series of impulses provided the impulses form a polarity code pattern corresponding to that station, means at said office controlled by the step-by-step mechanism at said office for disconnecting the line relay at said office from said line circuit and connecting said polar indication line relay in series in said 20 line circuit during the time spaces between said impulses, indication transmitting means at a particular station for transmitting an indication impulse of distinctive polarity from such station to said office for each time space when said indication line relay is included in said line circuit, and indication means in said office responsive to the repeated operation of said indication relay if the code pattern of the particular series of indication impulses corresponds to the code for said 25 30 35 40 45 50 55 60 65 70 75 indication means.

9. A communication system for transmitting control codes from an office to any one of a plurality of stations and for transmitting indication codes from any one of said stations to said 45 office during the same cycle of impulses comprising, a single line circuit extending from said office through all of said stations, a line relay at said office and a polar line relay at each of said stations included in series in said line circuit, a 50 polar indication line relay at said office, means at said office for energizing said line circuit extending through all of said line relays by series of positive and negative polarity control impulses arranged in a pattern to define a polarity code, 55 step-by-step mechanism at said office and at each of said stations controlled solely by said impulses irrespective of their polarity, means at each field station controlled by the polar line relay at such station and the step-by-step mechanism at such station responsive to such series of impulses provided the impulses form a polarity code pattern corresponding to that station, means at said office controlled by the step-by-step mechanism at said office for disconnecting the 60 line relay at said office from said line circuit and connecting said polar indication line relay in series in said line circuit during the time spaces between said impulses, indication transmitting means at a particular station for transmitting an 65 indication impulse of distinctive polarity from such station to said office for each time space when said indication line relay is included in said line circuit, indication means in said office responsive to the repeated operation of said 70 75 indication means.

5 dication relay if the code pattern of the particular series of indication impulses corresponds to the code for said indication means, and lock-out means for allowing the indication transmitting means at only one of said stations to transmit indication impulses during a particular series of control impulses.

10 10. A communication system for transmitting controls from an office and transmitting indications from a field station during the same series of control impulses comprising, an office and a plurality of field stations, a single line circuit connecting said office and all of said field stations, a line relay at said office and a polar line relay at each of said field stations normally all connected in series, step-by-step mechanism at said office and at each of said stations controlled by its respective line relay, means at said office for applying a series of distinctive polarity control impulses on said line circuit to operate said polar line relays to distinctive positions and to operate said step-by-step mechanisms, code responsive means at each field station controlled in accordance with the polar positions assumed by its associated polar line relay on a plurality of steps, an indication line relay in said office, means controlled by the step-by-step means for excluding said office line relay from and including said indication line relay in said line circuit during each time space between successive impulses, indication transmitting means at each field station for applying an indication potential on said line circuit for each time space to op-

erate said indication line relay, and locking means at each of said stations which are interlocked to render only one of said indication transmitting means effective at one time.

11. In a remote control system, a control office and a plurality of field stations connected by a line circuit, means including a first source of direct current in said office for intermittently energizing said line circuit with a series of time spaced direct current impulses, step-by-step mechanism at said office and at each of said stations operable in synchronism by said time spaced impulses, a second source of direct current at each of said stations, means at each of said stations effective during each time space to prevent the step-by-step mechanism at such station from being controlled by an impulse on said line circuit and for selectively connecting the associated second source of direct current to said line circuit in normal or reverse direction or to leave 20 said second source of direct current disconnected to form a plurality of code characters one character for each time space, means at said control office effective to disconnect said first source of current and said office step-by-step mechanism 25 from said line circuit during each time space; and means at said control office connected to said line circuit only during said time spaces and controlled by said code characters for registering a separate one of said stations in said control 30 office.

WILLIAM D. HAILES.
